J. GARAY.
COMBINED RAIL CHAIR AND JOINT.
APPLICATION FILED SEPT. 21, 1914.

1,141,954.

Patented June 8, 1915.

UNITED STATES PATENT OFFICE.

JOHN GARAY, OF FILBERT, WEST VIRGINIA.

COMBINED RAIL CHAIR AND JOINT.

1,141,954.

Specification of Letters Patent.

Patented June 8, 1915.

Application filed September 21, 1914. Serial No. 862,758.

To all whom it may concern:

Be it known that I, JOHN GARAY, a subject of the King of Hungary, residing at Filbert, in the county of McDowell and 5 State of West Virginia, have invented certain new and useful Improvements in Combined Rail Chairs and Joints, of which the following is a specification, reference being had therein to the accompanying drawing.

10 This invention relates to a combined rail chair and joint and has for its object to provide a device of such class, in a manner as hereinafter set forth, for securing the meeting ends of a pair of track rails together, at the same time providing for the necessary expansion and contraction due to 15 climatic conditions.

A further object of the invention is to provide a combined rail chair and joint 20 formed of a plurality of sections, having inner engaging means for clamping the sections to a pair of track rails, and further having means engaging in the track rails to prevent lateral, longitudinal, and vertical 25 movement with respect to the said sections.

Further objects of the invention are to provide a combined rail chair and joint which is simple in its construction and arrangement, strong, durable, efficient and 30 convenient in its use, readily set up and comparatively inexpensive to manufacture.

With the foregoing and other objects in view the invention consists of the novel construction, combination and arrangement of 35 parts as hereinafter more specifically described and illustrated in the accompanying drawings wherein is shown an embodiment of the invention, but it is to be understood that changes, variations and modifications 40 can be resorted to which come within the scope of the claims hereunto appended.

In the drawings wherein like reference characters denote corresponding parts throughout the several views, Figure 1 is a perspective view of a pair of track rails, broken away, showing the adaptation thereto of a combined rail chair and joint in accordance with this invention. Fig. 2 is a perspective view of the combined splice bar and chair section of the rail joint. Figs. 3 and 4 are perspective views of one of the members of the clamping section of the combined rail chair and joint. Fig. 5 is a perspective view of a locking member for the members of the 50 clamping section. Fig. 6 is a perspective view

view showing the manner of assembling the clamping sections.

Referring to the drawings in detail 6 and 7 denote a pair of track rails and each includes a head 8, a web 9, and a base 10. 60

The rail chair and joint consists of a chair section and a clamping section and said chair section consists of a chair plate 11, cut away at one side, to provide a pair of oppositely extending spaced projections 12. 65 The other side of the chair plate 11 has formed integral therewith a vertically disposed flange 13, which terminates in an inwardly extending base flange 14, and a vertically disposed splice bar 15, which has 70 formed on its inner face a pair of inwardly extending pins 16, 17. The base flange 14 is spaced from the base 11, as well as extending substantially parallel therewith, thereby providing a pocket 18 for the reception of one 75 side of the bases 10 of the track rails, when the track rails are mounted upon the plate 11. The plate 11 is of greater width than the width of the bases 10 of the track rails whereby said projections 12 will be alined 80 exteriorly with respect to said bases 10.

When the track rails 6, 7, are mounted upon the chair plate 11, the pins 16, 17, extend through openings 19 formed in the webs 9, as clearly illustrated in Fig. 1, and 85 said pins 16, 17, prevent longitudinal movement of the track rails with respect to each other.

The clamping section consists of a pair of members which are hinged to the plate 11 90 and each of said members consists of a bottom plate 20, and a top plate 21, the latter being of materially less width than the bottom plate 20 and the said plates overlap and are connected together by a rounded coupling portion 22, which is of less length than the length of said plates 20 and is flush with the inner ends of said plates 20, thereby providing clearances 23. One outer corner of the bottom plate 20 is connected to 95 one outer corner of the top plate 21 by a pin 24, the latter being arranged near the clearances 23. The pins 24 are positioned inwardly with respect to the projections 12 whereby the members of the clamping section are hinged to the plate 11. Each of the bottom plates 20 is formed with a segment-shaped slot 25 and extending into said slots are lugs, as seen in Fig. 6 of the drawing, carried by the lower face of the plate 11. 100 105 110

One of the members of the clamping section overlaps the other member of the clamping section and both members of the clamping section overlap the bases 10 of the track rails and the chair plate 11 and when the members of the clamping sections are in a position shown in Fig. 1, they are maintained in such position by a pivoted locking member which consists of a bar 26, pivoted 5 as at 27, to the upper member 28 of the clamping section and said bar 26 is provided with a lug 29, which is adapted to engage in openings 30 formed in the tops 21 of the members of the clamping section. The 10 other member of the clamping section is indicated at 31 and when the member 28 and member 31 are in a position shown in Fig. 1 the slots 30 aline whereby the lug 29 can extend into both of the slots and hold the 15 members of the clamping section in position shown in Fig. 1. When the device is assembled the clamping members are swung horizontally about the pins 24. The members of the clamping section, when the locking member is moved to a released position, 20 can be swung outwardly and the track rail removed.

What I claim is:—

Copies of this patent may be obtained for five cents each, by addressing the "Commissioner of Patents, Washington, D. C."

1. A combined rail chair and joint comprising a chair plate formed with a vertically disposed splice bar having pins capable of engaging in the webs of a pair of track rails, said splice bar including a base overlapping the bases of the track rails, and a clamping section consisting of a pair of members hinged to said chair plate and capable of being swung to overlap the bases of a track rail.

2. A combined rail chair and joint comprising a chair plate formed with a vertically disposed splice bar having pins capable of engaging in the webs of a pair of track rails, said splice bar including a base overlapping the bases of the track rails, and a clamping section consisting of a pair of members hinged to said chair plate and capable of being swung to overlap the bases of a track rail, and means for locking said members together.

In testimony whereof I affix my signature 50 in the presence of two witnesses.

JOHN GARAY.
